(57) **CLAIM**

The ornamental design for a fleece top, as shown and described.

DESCRIPTION

FIG. 1 is a perspective view of a fleece top showing my new design;

FIG. 2 is a front elevational view thereof;

FIG. 3 is a rear elevational view thereof;

FIG. 4 is a right side elevational view thereof; and,

FIG. 5 is a left side elevational view thereof.

The shading on the exterior of the garment in FIGS 1-5 is representative of fleece.
